UNITED STATES PATENT OFFICE.

EMIL KLEINSCHMIDT, OF FRANKFORT-ON-THE-MAIN, GERMANY.

MANUFACTURE OF BRIQUETS OF COAL, COKE, TURF, IRON, OR OTHER ORES, OR THE LIKE.

1,207,180.

Specification of Letters Patent.

Patented Dec. 5, 1916.

Application filed October 3, 1916. Serial No. 123,483.

To all whom it may concern:

Be it known that I, EMIL KLEINSCHMIDT, citizen of Germany, residing at Frankfort-on-the-Main, Germany, have invented certain new and useful Improvements in the Manufacture of Briquets of Coal, Coke, Turf, Iron, or other Ores, or the like; and I do hereby declare the following to be a full, clear, and exact description of the invention, such as will enable others skilled in the art to which it appertains to make and use the same.

In manufacturing briquets from coal, coke, turf, iron or other ores or the like it is important that the binding medium should be thoroughly and evenly mixed with the material of which the briquet or brick is made.

In order to attain this object according to the present invention, the binding medium, mechanically or otherwise atomized or a suitably reduced binding medium is fed to the material of which the brick is made, while the latter is in motion so that all particles of the material are brought into intimate contact with the binding medium. In order to attain this object, the binding material is advantageously blown into or through the falling dust-like material in a direction substantially at right angles to the same as will be hereinafter particularly set forth.

In the accompanying drawings, Figure 1 is a diagram illustrating the apparatus in longitudinal section, Figs. 2 and 3 show means for rotating or oscillating the mixing drum, Fig. 4 is a modified form of the apparatus, Figs. 5 and 6 are diagrams illustrating other modifications and Fig. 7 is a cross sectional view of the apparatus illustrated in Fig. 6.

Referring first to Fig. 1; the organic, liquefiable substance, such as tar, pitch, asphalt or the like is blown into the open end of the drum *k* through an atomizing nozzle *r* from the receptacle *o*, the said drum being advantageously inclined so that the material will gravitate toward the outlet end of the same. The drum *k* is advantageously supported on rolls *l*, *l* which may be rotated in any known manner, for instance, by means of chain gearing from a motor *m*. The said drum may also be rotated from a pulley driven by suitable means (Fig. 2) or simply rocked by means of a crank disk *n* and connecting

rod (Fig. 3). The drum may also be provided inside with pins or inclined plates *p* (Figs. 2 and 3) to assist in mixing and transporting the material through the same. The atomizing nozzle consists of the interior outlet nozzle *q* having a stopper *r* and the exterior shell *s* forming an annular injecting nozzle which is supplied through a pipe *t* with a suitable pressure medium, such as steam or compressed air. By means of the pressure medium forced through the nozzle, the pitch, tar, asphalt or the like is atomized and forced into the drum in the form of a dry powder, which, if the apparatus is not used for making briquets, may be won or stored as bitumen dust. Baffle plates *u* displaced as regards each other are advantageously mounted at the outlet end of the drum to catch and throw down the binding medium dust. An exhauster or fan *v* may be mounted in proximity to the outlet end of the drum, by means of which the pressure medium for atomizing the bitumen may be drawn off and by which means also a slight draft will be produced inside the drum.

In order to force the atomized or finely divided binding medium substantially rectangularly through the briquet material, while the latter is showered down in finely divided form, the blades or ribs *p* are provided (Figs. 2 and 3) previously referred to which raise the particles as the drum is rotated or rocked, and then allow them to fall again, this action being repeated with all the particles during their passage through the drum. An even fall of all the particles is attained by properly regulating the swing of the drum. During this operation the particles of the material will only fall loosely together, so that as the drum is rotated they will fall without pressure against each other, so that each particle will be properly coated with the binding medium. Experiments have shown that the briquets made on this principle are very compact and tight, while there is no waste of binding medium, thus attaining great economy in the use of the latter.

In the device illustrated in Fig. 4 the material forming the briquet is filled into a hopper *a'*, which may be shaken, after the manner of a bolting sieve so that the material will pass evenly out of the same and fall in the form of a shower. The mate-

rial is then collected in the hopper b' and after having been provided with sufficient binding medium, it may be passed on directly to the briquet-press. It is however 5 advantageous to employ a bucket elevator $c' c^2$, or the like and to pass the material through further hoppers $a^2-b^2-a^3-b^3$. In order to properly blow in the binding medium in a very finely divided state, it is 10 advantageous to first pass the same through a wind or blower separator, as used for fining flour and indicated at d , the pitch leaving this apparatus at e in the form of fine pitch dust and passing into a storage 15 receptacle f whence it is fed by a plate h in suitable quantity to the injecting nozzle s . The coarser powder passing out at the bottom of the apparatus d may be ground again and again fed in or used for other 20 purposes. The nozzle s serves also in this case as a compressed air or steam jet to force the atomized material substantially at right angles through the falling briquet material. There will be practically no friction between 25 the particles which simply fall one on the other into the hoppers b', b^2, b^3 .

In Fig. 5 a further modification is illustrated in which the material passes down a series of steps i which are shaken or vibrated 30 by suitable means, so that in this case also the jet meets the material substantially at right angles. The short sliding movement of the particles on the steps i will not interfere with the coating of the same since the 35 layers are very thin and the friction consequently very slight.

In Figs. 6 and 7 a modification is illustrated in which the material, similar to the device shown in Fig. 1, is fed into a drum k 40 provided with blades or ribs p and in which the binding medium is employed in a liquid form. In this case the atomizing is effected by means of a perforated pipe w extending into the interior of the drum so that as illustrated in Fig. 7 the jets of the binding medium will meet the falling material and be blown through the same substantially at 45 right angles.

The above described process and appara-

tus may be employed in connection with 50 any kind of binding material, which may be atomized or reduced as previously mentioned either mechanically or in other suitable manner.

It may be mentioned that if a liquid binding medium is introduced by means of an injector nozzle or the like, the briquetting material and the binding medium may be combined immediately beyond the nozzle, so that the particles of the binding medium will 60 combine with the particles of the briquetting material while still in a finely divided liquid form.

It is self-evident that the binding medium may be blown in, in the manner described 65 with reference to Fig. 1, in that the binding medium particles are first converted into dry dust and then brought into contact with the briquetting material being sprinkled in.

I claim as my invention:—

1. The herein described method of manufacturing briquets, which consists in feeding briquet material into a container, moving said container to give the briquet material therein a rotary rising and falling motion, 75 whereby said material is loosened and agitated without stirring the same and spraying a binding material into said briquet material in a direction substantially at right angles to the falling motion of the briquet 80 material.

2. In an apparatus for the admixture of briquet material with binding material, the combination with an inclined drum open at both ends, of means for moving said drum 85 to give its contents a rotary rising and falling motion, means at one end of the drum for spraying thereinto a binding medium in a direction substantially at right angles to that in which the contents of the drum fall, 90 and a series of staggered baffle plates at the opposite end of the drum.

In testimony whereof I hereunto affix my signature in the presence of two witnesses.

EMIL KLEINSCHMIDT.
